UNITED STATES PATENT OFFICE.

JAMES PRENDERGAST, OF SYRACUSE, NEW YORK.

PUZZLE.

1,251,822.

Specification of Letters Patent.

Patented Jan. 1, 1918.

Application filed December 4, 1915. Serial No. 65,040.

To all whom it may concern:

Be it known that I, JAMES PRENDERGAST, a citizen of the United States, residing at Syracuse, in the county of Onondaga and State of New York, have invented certain new and useful Improvements in Puzzles; and I do hereby declare the following to be a full, clear, and exact description of the invention, such as will enable others skilled in the art to which it appertains to make and use the same.

This invention is a puzzle of that class wherein a predetermined number of movable elements bearing a designating number or figure are to be arranged in such a manner as to produce a predetermined sum or result.

The invention contemplates a series of rectangular members or blocks, each bearing a figure or designation, the object being to so arrange the blocks in rectangular formation that the sum of each horizontal and each vertical row of blocks, as well as the sum of the blocks forming the two main diagonal rows, will equal a predetermined amount, when added.

To enable others to more clearly understand the invention, reference is made to two embodiments of the invention in the accompanying drawings, wherein:

Figure 1 is a plan view of a series of rectangular blocks having numerals thereon from 1 to 100;

Fig. 2 designates an arrangement of the blocks with numerals from 1 to 80 so arranged that a space is left at the center of the group to facilitate moving the blocks within a receptacle.

In employing the puzzle with 100 blocks, numbered consecutively, the sum total of such numbers is 5050. Arranging these blocks in 10 rows of 10 blocks, each should total one-tenth of the whole, or 505. If it is desired to arrange the blocks in a container with a shifting surface, then 99 blocks may be employed and numbered from 1 to 99 respectively, in which event, each row should total 495, by reason of the omission of the block numbered 100.

In like manner, if 81 blocks are employed in rectangular formation of 9 rows of 9 blocks each, the rows should total 369, or one-ninth of the sum of 81 characters. When a block is omitted to permit of the shifting of the remaining blocks within the

receptacle, the 80 blocks are arranged in 9 rows to total 360.

In like manner, 64 blocks may constitute the puzzle and may be arranged with 8 rows, each row to total 260, such number being one-eighth of the sum of the 64 blocks. Where 49 blocks are employed, each row will total 175; the sum of a row where 36 blocks are employed should total 111; the sum of a row where 25 blocks are employed should be 65; the sum of a row where 16 blocks are employed should be 34 and where 9 blocks are employed in the puzzle, the sum of the row should be 15. In like manner, other combinations may be arranged.

Referring more particularly to the embodiment of the invention illustrated in Fig. 1, a given number of rectangular movable members, or substantially cubical blocks A are shown provided with a suitable indicating means on a face thereof. This indicating means, in the example illustrated in Fig. 1, is a numeral whereby the blocks are consecutively numbered from 1 to 100.

In this arrangement of the device, the puzzle may be provided with blocks in consecutive order or variously assembled, the player being required to solve the problem by arranging the blocks A in the manner illustrated in Fig. 1, so that the sum of each vertical row B will total 505, each horizontal row C will total 505, and the sum of the diagonally arranged blocks D and E will total 505. These blocks may be placed upon a flat surface and their relation changed by sliding them into their various positions, or they may be bodily lifted and changed to various positions, as desired.

In Fig. 2, however, I have illustrated an embodiment whereby a number of blocks, for example, 80 blocks, bearing numerals from 1 to 80 respectively, are so arranged in rectangular formation within a receptacle F that 8 rows reading from the vertical or horizontal are formed of 9 blocks each and one row reading from the vertical or horizontal comprises but 8 blocks each, thereby leaving a space G at substantially the central part of the solved puzzle. This space provides means whereby the various blocks may be shifted in the receptacle F to solve the problem of this arrangement, the sum of each of the 20 rows must be 360; that is, the sum of each of the 9 horizontal rows H should be 360, the sum of each of the verti-

cal rows I should be 360 and the sum of the two main diagonal rows J. K., should be 360.

A vacant space may be left anywhere in any arrangement of the squares except the one containing fifteen numbers; in that the vacancy occurs in eight different places in the eight different positions. The numbers can be placed in squares containing fifteen or sixteen numbers; they need not necessarily contain consecutive numbers. Several hundred puzzles may be arranged alternately to exhaust the whole 100 numbers all totaling different amounts.

Having thus described my invention, what I claim as new and desire to secure by Letters Patent of the United States, is:—

A puzzle comprising a casing, a series of

rectangular blocks having numerals indicated thereon in consecutive order, the blocks being so arranged in rectangular formation within the casing that a space is left for one block at substantially the center of the rectangular formation of blocks, whereby the sum of each vertical and horizontal row represented by the blocks and of the two main diagonal rows will equal a predetermined amount.

In testimony whereof, I affix my signature, in presence of two witnesses.

JAMES PRENDERGAST.
